(57) **CLAIM**

The ornamental design for a staple and tack puller, as shown and described.

DESCRIPTION

FIG. 1 is a perspective view of a staple and tack puller;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is additional perspective view thereof with the cap shown removed; and,

FIG. 9 is another additional perspective view thereof, shown in use.

The broken lines shown in the drawings form no part of the claimed design.
